UNITED STATES PATENT OFFICE.

HENRY SCHNEIDER, OF CHICAGO, ILLINOIS.

WINDOW-CLEANER.

1,205,398.

Specification of Letters Patent. Patented Nov. 21, 1916.

Application filed November 11, 1915. Serial No. 60,853.

To all whom it may concern:

Be it known that I, HENRY SCHNEIDER, a citizen of the United States of America, and a resident of Chicago, county of Cook, and 5 State of Illinois, have invented certain new and useful Improvements in Window-Cleaners, of which the following is a specification.

The main objects of this invention are to 10 provide an improved form of window cleaner and particularly one which is specially adapted for use on the motorman's window of a street car; and to provide a window cleaner that is simple and durable 15 and that can be readily attached to the window frame of any car without altering the construction of either the frame or the sash.

An illustrative embodiment of this invention is shown in the accompanying drawings, 20 in which: Figure 1 is a front elevation of a street car body with the improved window cleaner fastened in position on the frame of the motorman's window. Fig. 2 is a front elevation of the cleaner drawn on a larger 25 scale. Fig. 3 is a fragmentary detail showing the supporting mechanism for one end of the squeegee. Fig. 4 is a view taken on the line A—A of Fig. 3.

In the construction shown in the drawings 30 the window frame 1 of a street car 2 is shown provided with the improved cleaner attached adjacent to the sill thereof. The cleaner comprises a pair of supports 4 which may be readily attached by screws to the 35 window frame, each of said supports being provided with a bifurcated guide member 5 pivotally mounted thereon by suitable means such as rivets 6. The guide members 5 are slotted longitudinally to form guide 40 arms 7 which are spaced so as to embrace and slidably support a squeegee 8.

The squeegee 8 is urged into contact with the window 3 at all times by means of a 45 compression spring 9 surrounding a headed pin 10, and bearing between the squeegee and a lug 11 of the support 4.

The squeegee and its supporting guide members are mounted to have a yielding, pivotal movement in an upward direction 50 against the action of springs 12 acting between pins 13 on the supports 4 and pins 14 on lower arms 7 of the guide members 5. Movement of the guide members and squeegee in a downward direction is limited 55 by pins 15 on the supports 4.

The operation of the device shown is as follows:—In order to clean the window the operator need merely lower the window and return it to its closed position. The squeegee requires no attention and operates to 60 wipe the window both in its downward and its upward movement, regardless of what may be the particular arrangement for raising and lowering the window. The springs 9 urge the squeegee into contact with the 65 window pane at all times, and the pins 9 and bifurcated guide members 7 permit the squeegee to follow the window in case the arrangement is such as to require the window to be shifted out of its normal plane 70 for the purpose of lowering it. The heads or shoulders at the outer ends of the pins 10 limit the movement of the squeegee in its guides, so that it cannot become accidentally 75 disengaged therefrom.

In certain window constructions which are now in common use on street cars, the lower edge of the window rests in a grooved ledge on the sill when the window is in its closed position and the sill is provided with 80 a pocket rearward of this groove into which the window sash may be lowered for the purpose of opening the window, such pocket being normally closed by a hinged sill section which in its closed position bears 85 against the lower part of the window sash and locks the same in its closed position.

The action of the squeegee is such that the window is wiped as it descends into the pocket and is again wiped as it is lifted from the pocket. During the operation of lifting the window and sliding it forward to its closed position, the squeegee swings upward and slides in the bifurcated guides, but is held into contact with the window by the 90 springs 12 and 9, as will be readily seen 95 from a consideration of the drawings.

Although but one specific embodiment of this invention has been herein shown and described, it will be understood that some of the details of the construction shown may be altered or omitted without departing from the spirit of this invention as defined by the following claims.

I claim:

1. A window cleaner, comprising supports, bifurcated guide members pivotally mounted on said supports, yielding means for resisting pivotal movement of said guide members, a squeegee slidably mounted on 110

said guide members, and a spring bearing between said support and squeegee for shifting said squeegee on said guide members.

2. A window cleaner, comprising supports, guide members pivotally mounted on said supports, yielding means for resisting pivotal movement of said guide members, a squeegee mounted in said guide members, a pin mounted on said squeegee and passing

through a lug on said support, a spring surrounding said pin and bearing between said squeegee and lug for shifting said squeegee in said guide members, and means on said pin for limiting the movement of said squeegee. 10

Signed at Chicago this 27th day of Oct., 1915.

HENRY SCHNEIDER
